FUEL PUMP

Walter F. Green, Canton, Ohio, assignor to The Timken Roller Bearing Company, Canton, Ohio, a corporation of Ohio

Application May 25, 1938, Serial No. 209,866

3 Claims. (Cl. 103—42)

This invention relates to pumps, particularly fuel pumps of the kind operated by or in unison with an internal combustion engine for supplying fluid fuel to the charge forming device thereof. The invention has for its principal objects to provide a strong, compact and durable oil tight pump of simple and economical construction, to facilitate assembly and disassembly of the parts, to provide separate, readily accessible manually operable means for priming and flushing the pump, to provide for by-passing or returning the fuel to the supply passageway of the pump when the discharge pressure in the pump cylinder rises above a predetermined limit and to utilize the pump priming means of the pump to indicate when the pump is by-passing fuel. The invention consists in the pump and in the construction, combinations and arrangements of parts hereinafter described and claimed.

In the accompanying drawings, wherein like symbols refer to like parts wherever they occur—

Fig. 1 is a plan view of a fuel supply pump embodying my invention.

Fig. 2 is a vertical section along the axis of the main pump cylinder on the line 2—2 in Fig. 1,

Fig. 3 is a vertical section taken through the pump along the axes of the diametrically opposed inlet and discharge passageways on the line 3—3 in Fig. 1,

Fig. 4 is a vertical section along the axis of the cylinder of the manually operable priming device for the pump; and

Fig. 5 is an enlarged detail section through the combined inlet and relief valve portion of the pump.

The pump shown in the accompanying drawings comprises a housing 1 having a central horizontal bore 2 extending from the back face of said housing and terminating short of the front face thereof. Press-fitted in the bore 2 of the pump housing 1 is a hollow cylindrical sleeve or liner 3 which is open at both ends and has a collar 4 at its outer end that abuts against the back face of said pump housing. The inner end portion 5 of the liner 3 is of smaller diameter than the bore 2 and terminates short of the inner end thereof, thereby forming an annular passageway 6 around said portion of said sleeve and a space 7 opposite the inner end thereof that establishes communication between said annular passageway and the interior of said sleeve.

Mounted in the liner 3 for reciprocating movement between the open inner end thereof and an annular shoulder 8 therein intermediate the ends thereof is a piston 9 having a rod 10 on its shoul-

der opposing end that terminates at its outer end in an enlarged head or collar 11. Sleeved on the piston rod 10 between the internal shoulder 8 of the liner 3 and a horseshoe washer 12 that straddles said rod and abuts against the head 11 thereof is a coil compression spring 13 whose expansive effort produces the suction stroke of the piston 9. This arrangement of parts permits the liner 3, piston 9, rod 10, washer 12 and spring 13 to be inserted in and removed from the pump as a complete preassembled unit. The pressure or delivery stroke of the piston 9 is produced by a power operated tappet or edge cam 14 which engages the bottom or closed end of a tappet cup 15 that is mounted for reciprocating movement in the liner 3 between the internal shoulder 8 thereof and the outer end thereof. The open end of the tappet cup 15 faces the internal shoulder 8 of the liner 3 with its bottom; and the bottom of said cup has a convex exterior surface 16 that is held in engagement with the cam or tappet 14 by the head 11 of the spring-pressed piston rod 10.

The pump housing 1 has horizontally disposed, diametrically opposed inlet and outlet passageways 17 and 18 therein that communicate with the annular passageway 6 between the pump housing bore 2 and the reduced inner end portion 5 of the liner 3. The inlet passageway 17 is provided with an outwardly open pressure relief or by-pass valve 19 and an inwardly opening suction or inlet valve 20. The relief valve 19 comprises a cylindrical sleeve that is axially slidable in a cage 21 having its inner end supported in the inlet passageway and its outer end supported in the enlarged or counterbored inner end portion of the axial bore of a fitting 22 that is threaded into the outer end of said passageway. The relief valve 19 has a beveled inner end portion that is normally held against a seat 23 provided therefor near the inner end of the inlet passageway by means of a coil spring 24 interposed between the outer end of said valve and the shoulder formed by the counterbored portion of the bore in the fitting 22, which bore constitutes a part of said passageway. The cage 21 for the relief valve 19 has longitudinal notches 21a that lead inwardly from the opposite ends thereof and communicate with an annular chamber 25 that surrounds said cage.

The inlet valve 20 comprises a ball that is held against a seat 26 provided therefor in the inlet end of the relief valve 19 by means of a spring 27 interposed between said ball and an internal shoulder 28a provided therefor at the inner end 55

of a valve guide 28, which is mounted in said relief valve between the valve seat at the outer end thereof and a snap ring 29 at the inner end thereof. The inlet valve guide 28 is provided 5 with a series of longitudinal notches 30 that lead inwardly from the outer end thereof and permit passage of the fuel around the inlet valve 20 when the latter is lifted off its seat 26.

The outlet passageway 18 is provided with an 10 outwardly opening check valve 31 in the form of a ball that is yieldably held against a seat 32 provided therefor in said outlet passageway by means of a coil spring 33 interposed between said ball and the inner end of a fitting 34 which is 15 threaded into the outer end of said outlet passageway and constitutes a portion thereof. The outlet valve 31 is supported in a guide sleeve 35 mounted in the outlet passageway 18 between the seat 32 therein and the fitting 34 and is provided 20 with a series of circumferentially spaced elongated notches 35a which permit the fuel to pass around said outlet valve when the latter lifts off said seat. A branch passageway 36 leads upwardly from the discharge passageway outwardly 25 of the outlet valve 31 and has its upper end closed by a hollow fitting 37 which forms an air chamber for partially dampening the impulses from the piston.

The hereinbefore described pump is also provided 30 with a manually operable auxiliary pumping device for priming the pump and clearing the fuel system of air. This priming device comprises a piston 38 reciprocable in the axial bore 39a of an upright extension 39 of the pump 35 housing 1. The inner end of this bore communicates through a passageway 40 with the annular passageway 6 between the inner end portion of the liner 3 and the horizontal bore 2 provided therefor in the pump housing. The inner end 40 of the auxiliary piston 38 is provided with a gasket 38a adapted in the innermost position of the piston to seat against an annular shoulder 41 provided therefor in the bottom of the bore 39a and thus cut off communication between said 45 bore and the main bore 2 of the housing during normal operating pressures of the pump. The piston 38 is provided with an upwardly extending rod 42 that terminates at its upper end in a head 42a. This rod is slidably supported in the 50 axial bore of a sleeve 43 that extends downwardly into the bore 39 and is slidably supported in a bushing 44 mounted in the upper end of said bore between a shoulder thereof and a snap ring 45. The exposed upper end of the sleeve 43 is shaped to provide a handle or knob 46; and the upper end of the piston rod receiving bore of 55 said sleeve is counterbored to accommodate the head 42a of the piston rod. The knob 46 has a base flange 47 that seats against the upper end of the upright housing extension 39 in the inoperative position of the sleeve 43 and is releasably held in such position by means of a spring clip 48 that is secured to said housing extension and 60 terminates at its upper end in a hook 49 adapted to snap over said base flange of said knob. The lower end of the sleeve 43 terminates short of the piston 38, and a coil compression spring 50 is sleeved on the piston rod 42 between the opposing ends of said sleeve and said piston.

The operation of the pump is as follows: When the tappet cup 15 is in contact with the drop of the cam 14 the suction stroke is imparted to the piston 9 by the spring 13, thereby 75 lifting the inlet valve 20 off its seat and drawing

fuel through the annular passageway 6 and space 7 into the chamber or cylinder formed between the opposed inner ends of said piston and the bore 2. When the tappet cup 15 is forced inwardly by the rise of the cam 14, the piston 9 is forced inwardly in the supporting sleeve 3, thereby forcing the fuel admitted through the inlet valve 20 out through the outlet valve 31 into the outlet passageway 18 and thence to the fuel injection pump or other charge forming device (not shown). When the quantity of fuel drawn into the pump is greater than that required by the charge forming device, a back pressure is created in the pump cylinder and when such back pressure is sufficient to overcome the pressure of the relief valve spring 24, said pressure lifts the relief valve 19 off its seat and causes a return flow of the fuel to the inlet side of the inlet valve 20 through the by-pass formed by the relief valve cage notches 21a and 20 the annular chamber 25. This by-passing of the fuel continues until the pressure in the pump returns to normal, whereupon the relief valve 19 closes and the fuel is discharged through the discharge valve 31.

When it is desired to flush or prime the pump, the hold down clip 48 is disengaged from the base flange 47 of the knob 46 and the auxiliary piston 38 is manually reciprocated by means of said knob to draw fuel through the inlet valve 20 into the main pump chamber and discharge said fuel through the outlet valve 31. In the latched position of the auxiliary piston 38, the spring-pressed gasket 38a at the lower end thereof serves to cut off communication between the auxiliary and main cylinders of the pump. In this position of the auxiliary piston 38, the gasket seating spring 50 is not fully compressed during the normal operating pressures of the pump. When, however, the pump is operating against a back pressure sufficient to cause bypassing of the fuel, the impulses from the main piston serve to further compress the spring 50 and impart a rapid reciprocatory or jiggling movement to the auxiliary piston and to the exposed head 42a of the rod 42 thereof, which movement of said head indicates to the operator that the pump is by-passing fuel.

While I have described my pump in connection with a supply pump for a fuel injection system of an internal combustion engine, it is obviously adapted for other uses.

What I claim is:

1. A pump comprising a housing having a cylinder, inlet and outlet passageways communicating with said cylinder, a piston in said cylinder, an inlet valve in said inlet passageway, means adapted upon a predetermined pressure in said cylinder to permit fluid, after passing through the inlet valve to be returned by-passed to said inlet passageway on the inlet side of the last mentioned valve, said housing having a second cylinder communicating with said end of said first mentioned cylinder, a priming piston reciprocable in said second cylinder, and means located exteriorly of said housing for manually reciprocating said priming piston, said priming piston being reciprocable by the impulses from said first mentioned piston during such predetermined pressure to thereby continuously reciprocate said manually operable means and thus indicate that the pump is by-passing fluid.

2. A pump comprising a housing having a cylinder and inlet and outlet passageways com-

- communicating with said cylinder, a piston in said cylinder, an inlet valve in said inlet passageway, means operable by a predetermined pressure in said cylinder to permit fluid admitted by said inlet valve to be by-passed to said inlet passageway at a point therein in advance of said inlet valve, said housing having a second cylinder therein opening into said end of said first mentioned cylinder, a priming piston reciprocable in said second cylinder and means located exteriorly of said housing for manually operating said priming piston, said priming piston being adapted to be continuously reciprocated by the impulses from said first mentioned piston only during such by-pass pressure, thereby imparting a continuous reciprocating movement to the exteriorly located operating means for said priming piston, whereby such continuous movement of said means indicates such by-passing of the fluid.
3. A pump comprising a housing having a cylinder and inlet and outlet passageways communicating with said cylinder, a piston in said cylinder, an inlet valve in said inlet passageway, means for by-passing fluid around said inlet valve from the discharge side thereof to the inlet side thereof upon a predetermined pressure in said cylinder, said housing having a second cylinder therein opening into said end of said first mentioned cylinder, a priming piston reciprocable in said second cylinder, a sleeve reciprocable in said second cylinder and having an operating knob located exteriorly thereof, means for locking said sleeve in its innermost position, a rod fixed to said priming piston and extending through said sleeve and terminating at its outer end in a head seated in a recess provided therefor in said knob, and a spring sleeved on said rod between said sleeve and said priming piston and adapted in the locked innermost position of said sleeve to hold said priming piston in its innermost position except under by-passing pressure during which the impulses from said first mentioned piston will continuously reciprocate said priming piston against the pressure of said spring and thus impart a similar movement to said rod and the exposed head thereof to thereby indicate by-passing of the fluid.
